UNITED STATES PATENT OFFICE.

WILLIAM CHURCHILL, OF CORNING, NEW YORK, ASSIGNOR TO CORNING GLASS WORKS,
A CORPORATION OF NEW YORK.

DESIGN FOR A TRANSPARENT COOKING-DISH COVER.

48,168.

Specification for Design.

Patented Nov. 23, 1915.

Application filed September 8, 1915. Serial No. 49,639. Term of patent 14 years.

To all whom it may concern:

Be it known that I, WILLIAM CHURCHILL, a citizen of the United States, residing at Corning, in the county of Steuben and State of New York, have invented a new, original, and ornamental Design for a Transparent Cooking-Dish Cover, of which the following is a specification, reference being had to the accompanying drawing, forming part thereof.

In the drawing, Figure 1 is a perspective view of a cooking dish cover showing my design as it appears to the eye, and Fig. 2 is a side view thereof.

Copies of this patent may be obtained for five cents each, by addressing the "Commissioner of Patents, Washington, D. C."

The cover is made of transparent material whereby not only can the observer see parts presented to him but whereby he can see through the walls of such parts other parts located therebehind.

I claim:

The ornamental design for a transparent cooking dish cover, as shown.

WILLIAM CHURCHILL.
